SALISBURY M. DAY, OF ROCHESTER, NEW YORK, ASSIGNOR TO GENERAL RAILWAY SIGNAL COMPANY, OF GATES, NEW YORK, A CORPORATION OF NEW YORK.

INDICATION FOR COLOR LIGHT SIGNALS.

Application filed April 3, 1923, Serial No. 629,627. Renewed April 5, 1927.

This invention relates to interlocking systems employing color light signals, and more particularly to indicating means governed by such signals for unlocking the signal levers and giving a visual indication in the signal tower.

In alternating current interlocking plants where a reliable source of alternating current is available, it is found economical and desirable to use distinctive aspect color light signals energized by alternating current instead of the usual semaphore signals. In systems of this kind, it is highly important that the control levers in the tower should have a position corresponding to the indication given by the respective signals. That is, if the lever of a particular signal is moved from the reverse or clear position toward the normal or danger position, the completion of the stroke of this lever to the full normal position should not be possible unless the signal controlled thereby actually indicates danger. This is important because the movement of a signal lever in an interlocking plant of the usual construction, when moved to the full normal position, will unlock other and conflicting levers operating signals of conflicting routes, derails, switches, and the like.

With the above and other considerations in mind, it is proposed in accordance with the present invention to provide the usual signal lever having an indication magnet with means for energizing this magnet only if the light signal associated therewith is indicating danger, this means to be of a construction to facilitate adjustment of the various constants, especially the voltage applied to the respective lamps of the light signals; and also of a construction in which many of the electrical circuits are entirely insulated from the rest, which to a large extent assures against detrimental and dangerous crosses and grounds.

Other objects, purposes and characteristic features of the invention will appear as the description thereof progresses.

In describing the invention in detail, reference will be made to the accompanying drawings, in which:

Figure 1 shows the invention applied to one form of semi-automatic block signal system, in which the various devices are shown

in a diagrammatic and simplified manner so as to avoid complicating the description of the novel combination shown; and

Fig. 2 shows in a schematic manner an application of the principles of the invention to a so-called two-arm interlocked signal.

Referring to the drawings, in which one arrangement of circuits and devices employing the present invention has been illustrated, the rails 1 of the usual railway track are divided by insulating joints 2 into blocks in the usual way, the block I and the adjacent ends of two other blocks H and J being shown. This section of trackway may for convenience be assumed to be automatic block signal interlocking territory, where the signals are semi-automatically controlled, that is, are controlled both manually and automatically and assume a condition corresponding to the most unfavorable condition of the two controls effected at any time. Obviously, the invention may be applied in other types of systems, but for convenience only one particular type has been illustrated. Since the several blocks in the particular system illustrated are the same, like parts and circuits of the various blocks have been given the same reference characters with distinctive exponents.

Each of the blocks is provided with a track transformer 3 and a track relay T, which in combination with the track rails form the usual closed track circuit. At the entrance to each block there is provided a distinctive aspect light signal Z, which in the particular arrangement shown is provided with three independent lamps designated G, Y and R and provided with color screens colored green, yellow and red, respectively, each of the lamps being energized by separate transformers 12, 13 and 14 respectively, as shown. Adjacent to each of the signals Z is provided a home relay HR and a distant relay D. These relays, in conjunction with the track relay T and a signal lever L, are adapted to control the indication of the lamps G, Y and R of the signal Z.

In the interlocking tower is provided a manually operable lever L, which with its associated parts comprises a portion of a well-known dynamic indication interlocking system, and therefore will not be described in detail. It may, however, be stated that

the coils 4 and armature 5 are parts of an indication magnet IM, which in connection with the detent 6 is adapted to release the lock dog 7 from the locking shoulder 8 of the lever L when this lever is being operated from the reverse toward the normal position. The lever is locked in the half normal position by the engagement of this locking shoulder 8 with the lock dog 7 during this direction of movement. This locking of the lever L in the half normal position persists until an indication current is received by the coils 4 of the indication magnet IM. A momentary flow of current through these coils 4, with the lever in the half normal position, causes the armature 5 to be attracted to move the detent 6 from under the lock dog 7, whereby the spring 9 moves the lock dog 7 to its ineffective position, thus enabling the tower attendant to move the lever L to the normal position and in turn unlock certain other conflicting levers.

It should be noted that movement of the lever L toward the left, that is, toward the reverse position, will not cause it to be effectively locked when reaching the half reverse position. Although the righthand end of the lock dog 7 would be moved upward and retained there temporarily by the detent 6, as the lever is moved toward the left the projection 10 rocks the unlocking cam 11 which in turn strikes the tail piece of the detent 6, thereby unlocking this lever. That is, the lever L is locked in both the half normal and the half reverse positions, but upon movement of the lever to the reverse position mechanical unlocking takes place regardless of the condition of the distant signal; whereas movement of the lever toward the right, that is, toward the normal position does not cause such unlocking and the unlocking in this instance must be accomplished by the energization of the indication magnet IM.

In the interlocking tower are also provided relays for controlling the flow of current to the indication magnet IM and to suitable pilot signals. In the particular arrangement shown, a clear and caution relay GYR, and a danger relay RR, have been shown. These relays also control the pilot lamps GY and Re.

The individual transformers 12, 13 and 14, having their secondaries separately connected to the lamps G, Y and R respectively, are of a special construction. These transformers are designed and constructed to have characteristics similar to both a potential transformer and a current transformer of the type well-known and used in commercial alternating current lighting and power systems. That is, each of these transformers is constructed to give a substantially constant voltage at its secondary terminals when the primary winding is connected in series with one of the relays GYR or RR and a source

of energy, and will in turn energize such relay to move it to the energized position when the secondary winding of such transformer is closed through a signal lamp having its filament or filaments intact; but on the other hand requires a very small exciting current, insufficient to move the relay to the energized position, if its secondary winding is open for any reason.

The lamps G, Y and R are preferably of the multiple filament type, that is, are preferably constructed with two filaments connected in multiple, so that, if one of the filaments burns out, an effective but weakened signal will still be given whereby information will be conveyed to the train crew and yard workmen that the signal lamp is partially burned out. Also, the relays GYR and RR in the tower may be so adjusted that they will not be moved to the energized position by the current flowing in the primary winding of the particular transformer 12, 13 or 14, to which they are connected when the lamp connected to the secondary winding of such transformer has one of its filaments burned out. Thus, by this construction, not only will it be possible to tell when a signal lamp is partially burned out by looking at such signal lamp from a distance but this will be indicated in the tower also, so that such lamp may be immediately replaced.

Operation.

The signal lever L and the signal Z controlled thereby have been shown in their normal danger condition, with the block to the entrance of which this signal is placed and the next block in advance thereof unoccupied and in their clear traffic condition. Under this condition, the track relay T at the entrance of the block I is energized by track circuit current from the track transformer 3. Since the lever is in its normal danger position, the home relay HR and the distant relay D are deenergized. With these latter relays deenergized, the transformer 14 associated with the red lamp R is energized through the following circuit:—Beginning at the secondary winding of the transformer 20, wires 21 and 22, primary winding of the transformer 14, wire 23, back contact 24 of the distant relay D, wire 25, back contact 26 of the home relay HR, wire 27, relay RR, wires 28 and 29 back to the secondary winding of the transformer 20, thereby illuminating the red lamp R by energy derived from the secondary of this transformer.

With this red lamp R taking current from the secondary winding of the transformer 14, a proportional current will flow in the primary winding which is sufficient to maintain the relay RR in the tower in its energized position. This red lamp R is connected to the proper tap of the secondary winding of

the transformer 14, only three taps 30, 31 and 32 having been shown. The transformers 12 and 13 have similarly been provided with taps, so that the desired number of 5 turns may be connected to the respective lamps connected to these transformers.

With the relay RR energized, as just explained, the pilot lamp Re in the tower is energized by current flowing through a circuit comprising the secondary winding of 10 a transformer 33, wires 34 and 35, the red pilot lamp Re, wire 36, front contact 37 of the danger relay RR, wire 38, back contact 15 39 of the clear and caution relay GYR, wire 40 back to the secondary winding of the transformer 33.

Danger to clear—manually.—If the lever L is moved to the reverse or extreme left position, a circuit will be completed which 20 may be traced as follows:—Beginning at the secondary winding of the transformer 33, wire 43, spring contact 44, contact block 45 of the lever L, spring contact 46, wire W, front contact 47 of the track relay T, wire 48, winding of the home relay HR, wires 49, 50 and 25 51 back to the secondary of the transformer 33. The completion of this circuit energizes the home relay HR which interrupts the circuit for the danger relay RR in the 30 tower by the lifting of back contact 26, and also completes a circuit for the distant relay D which may be traced as follows:—Beginning at the secondary winding of the transformer 53¹, wire 54¹, front contact 55¹ 35 of the track relay T¹, wire 56, front contact 57 of the track relay T, wire 58, front contact 59 of the home relay HR, wire 60, winding of the distant relay D, wires 61, 50 and 62 back to the secondary winding of 40 the transformer 53¹.

This energization of the relays HR and D completes an energizing circuit for the primary winding of the clear transformer 12 as follows:—Beginning at the secondary 45 winding of the transformer 20, wires 21, 63 and 64, primary winding of the transformer 12, wire 65, front contact 66 of the distant relay D, wire 67, front contact 68 of the home relay HR, wire 69, front contact 70 of the track relay T, wire 71, winding of the 50 clear and caution relay GYR, wires 72 and 29 back to the secondary winding of the transformer 20. This flow of current through the primary winding of the clear transformer 12 and the relay GYR causes this relay to lift 55 its back contact 39, the red pilot lamp Re already having been extinguished by de-energization of relay RR and illuminating the clear and caution pilot lamp GY. This lamp GY is energized through a circuit including the secondary winding of the transformer 33, wire 40, contact 39 of the relay GYR, wire 74, lamp GY, wires 75 and 34.

Clear to danger—automatically.—If a 60 train now passes through the block H in the

normal direction of traffic, as indicated by the arrow, and passes into the block I, the track relay T is deenergized because it is being shunted by the wheels and axles of the vehicle. This causes the home relay HR 70 and the distant relay D both to become deenergized, as is readily apparent by looking at the drawing. The deenergization of the relays HR and D interrupts the circuit for the clear and caution relay GYR in 75 the tower, and again energizes the danger relay RR, which causes the lamp GY to be extinguished and the lamp Re to be energized, thereby informing the tower attendant that the block I is occupied by another 80 train. Since the danger lamp transformer 14 has its primary winding connected in series with the danger relay RR in the tower, the red lamp R of the signal Z is also illuminated, thereby giving the proper indication 85 to a following train attempting to enter the block I.

Danger to caution—automatically.—As the train, assumed to be occupying the block I, passes out of this block into the next block 90 J, the track relay T¹ at the entrance of the block J will be deenergized, thereby preventing the distant relay D from picking up even if the track relay T and the home 95 relay HR were energized, the energizing circuit for the distant relay D being broken at the front contact 55¹ of the track relay T¹. As the train leaves the block I, the track relay T is again energized. This causes the home relay HR to pick up for obvious 100 reasons, but does not cause the distant relay D to pick up for reasons just explained.

With the track relay T and the home relay HR in their energized position, and the distant relay D in its deenergized position, a 105 circuit for the caution transformer 13 may be traced as follows:—Beginning at the secondary winding of the transformer 20, wires 21, 63 and 78, primary winding of the transformer 13, wire 79, back contact 66 of the 110 distant relay D, wire 67, front contact 68 of the home relay HR, wire 69, front contact 70 of the track relay T, wire 71, winding of the clear and caution relay GYR, wires 72 and 29 back to the secondary winding of 115 the transformer 20. The completion of this circuit causes the lamp Y of the signal Z to be energized by current derived from the secondary winding of the transformer 13, consequently a proportional current will flow 120 in the primary winding of this transformer and through the circuit just traced, thereby energizing the clear and caution relay GYR in the signal tower which in turn completes a circuit heretofore traced for energizing the 125 clear and caution lamp G—Y.

Caution to clear—automatically.—As the train now considered to be moving in the block J passes out of this block in the direction of traffic, the track relay T¹ again be- 130

comes energized. This causes the energizing circuit for the distant relay D to again become completed as heretofore traced, thereby again energizing this relay and completing a circuit through the primary winding of the clear transformer 12 heretofore traced, thus causing the illumination of the green lamp G and causing a current proportional to the current consumed by this lamp 10 to flow through the clear and caution relay in the tower, thus maintaining it in its energized condition as it was prior to the clearing of this block J.

Clear to danger—manually.—Let us assume now that the tower attendant wishes to allow a train to move over an interfering track (not shown), such as a crossover. Before the attendant can allow such movement of a train over a conflicting route, he 20 must first remove certain derails, open certain switches or clear certain signals, which cannot be done until the lever L governing the signal Z of the block I shown has first been moved back to the normal position.

25 If now the lever L is moved toward the right, that is, toward the normal position, it can only be moved in this direction until the contact block 45 assumes the dotted position shown in the drawing. When the lever 30 L reaches this position, the right-hand end of the lock dog 7 will be engaged by the locking shoulder 8 of the lever L, this lock dog being held in the locking position by the detent 6. Since the contact block 45 35 does no longer bridge the spring contacts 44 and 46, the circuit for the home relay HR will be broken, thereby deenergizing the distant relay D for reasons heretofore described. Since the relays HR and D are now 40 in their deenergized position, the clear and caution relay GYR will be deenergized and the circuit including the danger relay RR in the tower and the primary winding of the danger transformer 14 at the signal Z will 45 be completed, thereby illuminating the red lamp R and causing a proportional current to flow through the winding of the danger relay RR, thereby moving it to its energized position.

50 With the relay GYR deenergized and the relay RR energized, a circuit may be traced through the indication magnet IM as follows:—Beginning at the secondary winding of the transformer 33, wire 82, back contact 55 83 of the relay GYR, wire 84, front contact 85 of the relay RR, wire 86, coils 4 of the indication magnet IM, wire 87, spring contact 88, contact block 45, spring contact 89 of the lever L, wire 90 back to the secondary 60 winding of the transformer 33. The completion of this circuit causes the armature 5 of the indication magnet IM to be attracted, thereby delivering a blow under the extending arm of the detent 6 whereby 65 the detent is disengaged, thus causing the

lock dog 7 to assume the unlatched position. This unlocking of the signal lever L allows the tower attendant to complete the movement of the stroke of the lever L to its full normal position, which in turn through the usual bar and tappet interlocking mechanism unlocks other conflicting levers.

It should be noted that when the lever L is moved to the half normal position, as just described, if one or both filaments of the lamp R is burned out at this time, it will be impossible for the lever to be unlocked to permit its movement to the full normal position. This is due to the particular construction of the transformers 12, 13 and 14 and the adjustment of the relays GYR and RR. If the red lamp is partially or wholly burned out, there is not enough current flowing through the primary winding of this transformer 14 to energize the danger relay 85 RR in the tower sufficiently to cause it to close its front contacts and complete a circuit, either for the pilot lamp Re or for the indication magnet IM. This characteristic of the transformer 14 is due to the fact that the sum of the exciting current and one half of the current flowing in the red lamp is smaller than the pick-up current for this relay. If it is desired to use single filament lamps instead of multiple filament lamps, the relays GYR and RR should be adjusted so that they will drop if only the exciting current of one of the transformers 12, 13 or 14 flows through its winding.

The construction of the transformers 12, 13 and 14 also permits various voltages to be applied to a particular type of lamp, or permits lamps of different voltages to be used, by connecting the lamps to the particular tap brought out of the secondary winding of these transformers. In the particular construction shown, only three taps, namely, 30, 31 and 32 have been illustrated, but any number of such taps may be employed if desired.

One characteristic of this invention, which will be readily appreciated from the foregoing explanation, is that the indication mechanism for a lever is controlled dependent upon the actual flow of current through the filament or filaments of the lamp for the red signal. In other words, the indication for the lever is dependent upon the actual aspect of the signal itself, so that unless the signal is actually giving a red or stop indication, no indication is received. It should be noted that this result is obtained without modifying the voltage or current requirements of the incandescent lamps themselves, as is the case whenever it is attempted to connect a means in circuit directly in series with the filament. Also, the operating characteristics of the relays RR and GYR, together with the characteristics of the transformers 12, 13 and 14 may be selected, as 130

above explained, so that the burning out of one filament of a double or duplex filament lamp will be manifested, thereby indicating to the attendant that a lamp has to be replaced.

Heretofore little attention has been given to determining automatically whether or not the lamp or lamps of a light signal are lighted. Ordinarily it is assumed that burning out of the lamps of a color light signal, or interruption of their energizing circuits, results in a so-called "dark" signal which if the engineer, by rule, will interpret as giving the unfavorable indication and stop, stay, or proceed, in accordance with the character of the signal and the rules of the road. It will be evident, however, that this theory of safety is based on the premise that the engineer will observe and recognize a "dark" signal; but as a practical proposition, it is not difficult for an engineer to miss a dark signal entirely, failing to notice the signal casing and observe that there is no lamp lighted. It is highly desirable, therefore, as far as consistent, with practical limitations, to provide a means of automatically detecting the burning out of the lamp of a light signal. Such automatic means has been provided by this invention.

This invention, in its broadest aspects, is applicable to various conditions found in practical railway signaling. The particular arrangement shown in Fig. 1 is merely typical. This arrangement illustrates how the indication mechanism of a lever may have its operation dependent upon the actual indication of the light signal, and also how suitable lamps or other indicators in the tower may be employed to keep the tower man advised regarding the actual indicating conditions of the several signals. In this connection it should be understood that the lamps GY and Re are preferably mounted in suitable casings directly above or below the corresponding lever L, or in a well defined relation thereto, so that the tower man can easily associate each lamp with its particular lever. Among other things, the indicator lamps GY and Re enable the tower man to discover at the earliest possible moment whenever the signal lamp of any one of the signals burns out or has its control circuit open, thereby permitting the defective lamp to be immediately replaced or the circuit failure repaired so as not to unnecessarily delay traffic movement or introduce a hazardous condition occasioned by a dark signal.

It will be observed that the relay RR accurately repeats the lighted condition of the red or danger lamp R, this relay when de-energized signifying that the red lamp R is for some reason extinguished. Such automatic detection of the failure of the red lamp R to give the desired stop indication may be utilized in ways other than control

of the indication mechanism and the indicator lamps GY and Re. An extra contact or contacts X, or a repeater relay controlled thereby, may be added to the relay RR and these additional contacts are employed to govern any circuit or circuits which it is desired in the interests of safety to break in the event that the red lamp R is out. Various arrangements employing such additional contacts to advantage will be readily appreciated by those skilled in the art. For example, the relay RR may be used to perform a function analogous to that of the so-called "SS relay" sometimes used in modern interlocking practice. Or, the contact X of the relay RR may be used to interrupt the control circuit of another signal or signals of conflicting routes.

As a typical specific example of the adaptability of the present invention to practical operating conditions, there is shown in Fig. 2 in a diagrammatic fashion the way in which the invention may be employed to electrically interlock or cross-check the indications of the "two-arm" interlocked signal, commonly used to signal traffic over a main or high speed route or over a diverging or low speed route. While the signaling practice for such conditions varies somewhat, ordinarily there is used what is termed a two-arm signal, this signal consisting of two separate signals one above the other. In Fig. 2 are shown two three-aspect light signals U and B mounted on the same pole. Call-on signals or other signals for giving additional aspects, sometimes used, have been omitted to avoid complication. Ordinarily, the uppermost signal U is used to govern traffic on the straight or high speed route M, and the lower signal B is used to indicate traffic conditions on the diverging route DR.

The control for the signals U and B governing the main and diverging route, respectively, have been shown in a very simplified and schematic manner in Fig. 2 of the drawings. Two levers L^a and L^b have been shown, which are adapted for controlling the signals U and B respectively, subject to automatic control in the same manner as shown in Fig. 1, only that the lever L^b is still further subjected or restricted, in that, it is at times locked in the normal position. The dotted rectangles R^a and R^b designate the relays T, HR and D governing the signals U and B respectively. The dot and dash line shown indicates the dividing line of the apparatus belonging to these two levers and signals.

In the particular arrangement shown, the danger relay RR of the lever L^a is provided with contacts X¹ and X², similar to the contacts X heretofore mentioned. The contact X¹ is connected in the wire W of the diverging route signal B substantially as hereto-

fore described, and the contact X^2 governs the control circuit for a lock magnet 100 for locking the lever L^b in its normal position when the danger relay RR associated with the lever L^a is deenergized. Similarly, the relay GYR of the lever L^a is shown in Fig. 2 with two back contacts Y and Y^1 , which are also included in said circuits.

In order to bring out the advantages and the safety afforded by the application of the invention to the arrangement illustrated in Fig. 2, let us assume that a train is approaching from the left and that the tower attendant has set up the diverging route for the train. With the diverging route set up, the upper signal U will normally indicate red (danger) as before, and the lower signal B will indicate green (clear) on the assumption that two blocks at least in advance on the diverging route are clear. In other words, the whole signal will indicate red over green which means to the engineer that he may proceed but must reduce his speed to take a diverging medium or low speed route.

If now the red lamp of the upper or main track signal U should burn out, a green light standing alone would remain, which might be mistaken by the engineer as a signal to proceed at high speed, with the result that the train would probably be derailed when taking the curve of the diverging route. This hazardous condition is avoided in the system shown in Fig. 2 in two different ways.

In the first instance, if the red lamp R of the main line signal U is not illuminated at the time the diverging route is being set up, the tower attendant would not be able to move the lever L^b to set up this route because the lock magnet 100 is not energized at this time, its energizing circuit being broken at the contact X^2 of the relay RR, this relay only being energized when the lamp R of the signal U is energized. That is, the tower attendant could not clear the lower signal B and would be forcibly and unmistakably informed that something was wrong, so that it could be immediately looked after and corrected. The whole signal then would have the appearance of one red light, which would signify stop.

In the second instance, if the red lamp of the main line signal U is intact, the tower man may set up the diverging route. Assuming, however, that the red lamp of the upper signal U fails sometime after the diverging route has been set up, the electric lock 100 on the lever L^b at this time is useless because the lever L^b had already been moved to its reverse position. This deenergization of the red lamp of the main route signal U will, however, deenergize the relay RR of the lever L^a , thereby deenergizing the relays HR and D included in the dotted rectangle R^b by interruption of the circuit through wire W, thus changing the indica-

tion of the lower diverging route signal B from clear or caution, as the case may be, to red (danger), which informs the engineer of danger ahead and causes him to take the proper precaution in moving up to this interlocking point.

In practice, a distant signal will be located some distance in the rear of the interlocking signals U and B, which might in some instances give the engineer additional information in case the red lamp of the signal U should burn out. Since, however, such failure of the lamp R might easily occur while the train is moving between the distant and the home or interlocking signal, this distant signal has not been shown in the application of the invention to a system such as shown in Fig. 2.

As an additional precaution the contacts Y and Y^1 of the relay GYR are included in the circuit for the lock magnet 100 and the control circuit for signal B, so that the green and yellow lamps of signal U must be out before the signal B can be changed to give a favorable indication.

While only certain specific applications of the invention have been shown and described, particularly with reference to interlocked signals, it will be evident to those skilled in the art that the invention is susceptible of other applications in practice; and it is desired to have it understood that various additions, substitutions, changes and modifications may be made in the particular arrangements shown and described so as to adapt the invention to other practical uses or applications, all without departing from the spirit and scope of the invention, or the broad idea of means constituting the invention.

What is claimed, is:—

1. In an interlocking system for railways, the combination with a multiple aspect color light signal including a danger lamp, and a transformer for energizing said danger lamp under predetermined conditions, of indicating means located at a distant point and in a circuit including the primary winding of said transformer for indicating whether or not said danger lamp is energized.

2. In a signal system for railroads, the combination with a light signal having an incandescent lamp, a transformer having its secondary connected in circuit with said lamp, and an energizing circuit for the primary of said transformer including a source of current and a relay, said relay having its energizing current reduced sufficiently to open its contacts when the impedance of the primary of said transformer is increased upon burning out of the lamp and cessation of flow of current in the secondary of said transformer.

3. A railway signal system comprising, a color light signal including an incandescent lamp, a transformer having a secondary

winding provided with a plurality of taps for energizing said lamp by any one of a large number of voltages, and means associated with the primary winding of said 5 transformer for indicating whether or not said lamp is energized to consume a predetermined amount of energy.

4. A railway signal system according to claim 3, wherein the lamp is provided with 10 two filaments in multiple, and in which the indicating means indicates whether or not both of said filaments are energized.

5. A railway signal system comprising, a color light signal including an incandescent 15 lamp, automatic traffic controlled means for illuminating said lamp if the block at the entrance to which the signal is placed or the next block in advance thereof are occupied, manually operable means for deenergizing 20 said lamp regardless of traffic conditions ahead, and indicating means responsive to the energization of said lamp.

6. In an interlocking system for railways, the combination with a multiple aspect color 25 light signal including a plurality of multiple filament lamps, each of said lamps being connected to the secondary winding of its individual transformer, and means associated with the primary windings of said 30 transformers for indicating the indicating condition of said signal and whether one filament of said multiple filament lamps is burned out.

7. A multiple aspect color light signal 35 comprising, a plurality of color light signals each having a signal lamp having two filaments, means for energizing any one of said lamps, and means for indicating if the particular lamp energized at the time has 40 both of its filaments intact.

8. In an interlocking system having two levers, a lock on one of said levers, a magnet associated with said lock, said lock locking said one lever when said magnet 45 is de-energized, a multiple aspect light signal associated with and controlled by said one lever, another multiple aspect light signal associated with and controlled by the other lever, and means for deenergizing said 50 magnet when one of the lights in said other multiple aspect light signal burns out.

9. In an interlocking system for railroads, the combination of a plurality of multiple aspect color light signals mounted one above 55 the other to indicate traffic conditions on two possible routes ahead, and means for locking the lever governing the lowermost signal when a lamp in the uppermost signal is extinguished.

60 10. An interlocking system for railroads comprising, two multiple aspect color light

signals one located above the other to give a compound indication, and means governed by the current for energizing a lamp of one of the signals for locking a lever governing the other signal or for effecting a danger indication by said other signal. 65

11. In a signal system for railroads, two light signals each constituting a separate light projecting device, said signals when 70 lighted giving indications corresponding to different traffic conditions, an incandescent lamp for each signal, and means for automatically lighting the lamp of one signal if the lamp of the other signal burns out when 75 it should be lighted.

12. In a signalling system for railroads, the combination with two railway tracks, of two multiple aspect light signals associated with said tracks each governing traffic 80 over only one of said tracks, manually operable levers for controlling the indicating conditions of said light signals, and means for locking the lever for controlling one of said light signals when a lamp in the other 85 light signal is burned out.

13. In a railway signal system, a light signal having a clear lamp and a danger lamp, a manually operable lever, having 90 clear and danger positions, for controlling the signal, an electrically operated detent for the lever preventing movement of the lever from its clear to its danger position when its control circuit is de-energized, a relay having a front contact in the detent 95 control circuit, and a transformer having its secondary in series with the danger lamp, and its primary in series with the said relay.

14. A light signal for railways comprising, two light projecting units, an incandescent lamp for each unit, control means for each unit and automatic means associated with the lighting circuit of one lamp for lighting the other lamp independently of its control means, said automatic means being effective whenever the lighting circuit of the first mentioned lamp is established and current fails to flow therein. 100

15. A light signal for railways comprising, two light projecting units, an incandescent lamp for each unit, control means for each unit and a relay controlled by the lighting circuit of one lamp, and having a contact controlling the lighting circuit of the other lamp independently of its control 110 means, said relay being effective whenever the lighting circuit of the first mentioned lamp is established and current fails to flow therein. 115

In testimony whereof I hereby affix my 120 signature.

SALISBURY M. DAY.
